UNITED STATES PATENT OFFICE.

ALFRED JAMES NEILL WALKER, OF LIVERPOOL, ENGLAND.

MANUFACTURE OF PRINTING-PLATES OR SURFACES FOR PRINTING FROM.

1,375,874.

Specification of Letters Patent. Patented Apr. 26, 1921.

Application filed January 25, 1918. Serial No. 213,788.

To all whom it may concern:

Be it known that I, ALFRED JAMES NEILL WALKER, a subject of the King of Great Britain, residing at Liverpool, in the county 5 of Lancaster and Kingdom of England, have invented certain new and useful Improvements in or Relating to the Manufacture of Printing-Plates or Surfaces for Printing From, of which the following is a 10 specification.

This invention has reference to certain improvements in making printing plates from celluloid, or other similar material that can be softened by heat.

15 One of the difficulties experienced in the molding of warm celluloid and like sheet material lies in the fact that gas or liquid emanates from the material during the process, and being trapped with perhaps 20 some air as well, between the pressing members so that it cannot escape, it causes striations or bubbles to be formed on the face of the product.

Heretofore in one method of molding 25 warm celluloid sheet material, fluid pressure has been employed in direct contact with the surface to be modeled thereby. This method involves practical inconveniences and moreover gives less satisfactory results 30 than does the process of the present invention. In another method rigid press plates operated at a high pressure were employed and the space between them containing the celluloid and the mold was made air tight 35 by a rubber packing. This space was put in communication with a vacuum so as to withdraw any air during the pressing process, and the mechanism was therefore somewhat complex. In yet another method the 40 celluloid was subjected to pressure between two faces one of which was rigid or hard and the other of which was an air pressure bag freely deformable by the surface (e. g. that of a photographic carbon negative)

45 against which it acted, the characteristic feature being the employment of a pressure sufficiently low to permit such gas or liquid as comes out of the celluloid or the like to escape laterally between any of the said 50 surfaces and issue at their edges into a region of still lower pressure. In other arrangements the space between the two faces (containing the celluloid) one of which was rigid and hard and the other was an air or 55 water bag, was made tight or the best possible fit, and no means whatever were pro-

vided for withdrawing the gas or liquid which emanates from warm celluloid, though in one instance it was proposed (in connection with apparatus for the pressing 60 of moldings in fibrous material agglomerated by means of an agglutinant) to clamp to the press table, a piece of knitted or other felt through the medium of a frame formed with projections to prevent the compression of the edges of the felt in the 65 spaces between the projection in order to permit of the expulsion of water and air contained in the material operated upon.

Now it is highly desirable that direct contact of the fluid under pressure with the celluloid should be avoided, and that while allowing high pressure to be employed so as to produce a celluloid plate which will take the place of the ordinary electroplate 70 or stereotype for printing letter press, pictures, posters, paper hangings and so on, will allow the gas or liquid that emanates from the warm celluloid to escape. By celluloid I mean not only celluloid itself, but 75 any material which is similar to celluloid in that when warmed and pressed it exudes gas and liquid.

My method consists in forming a matrix laying the same on the hollow table of a 80 press, providing in connection with the follower of the press a recess in its face to which an inflatable mattress is applied, laying on the matrix a sheet of celluloid or the like, then bringing the inflatable mattress 85 face of the follower toward the table so that while the mattress will lie against the sheet which slightly enters into the recess in the follower the rigid margins of the table and follower will be spaced apart or 90 leave clear passages between them to allow any gas or liquid coming out of the sheet to escape, admitting hot fluid under pressure 95 into the hollow chamber in the press table to warm the matrix and soften the sheet, inflating the mattress with air under pressure 100 to press the sheet into the matrix and finally releasing the pressure and charging the chamber with cooling fluid to harden the sheet. By this method the mattress 105 will impact against the sheet while the rigid margins of the table and follower will be spaced apart or leave clear passages between them to allow such gas or liquid as comes out of the sheet to escape laterally 110 through the passages between the table and follower, and also any air between the mat-

tress and sheet will be driven off there-through when the mattress is inflated. I am however aware that press plates have prior to this invention been provided with 5 hollow chambers which are charged with hot fluid to soften the celluloid &c. and subsequently with a cooling fluid to harden it.

The matrix itself is produced in the following manner. The type, engraved plate 10 or other surface to be printed from is set up by the compositor in the usual way, and a thin sheet of lead, vulcanite, or fiber is impressed upon the face of the form so as to produce a matrix. This is effected by a matrix 15 rolling machine, mangle or press wherein the form is brought into contact with the sheet of lead or other material and is impressed thereinto, so that an exact facsimile of the printing surface (set up by the compositor) is produced and forms the matrix. 20 This matrix constitutes a mold from which the printing plate is made.

In order that my invention and the manner of performing the same may be properly 25 understood and the improvements as compared with known apparatus may be differentiated I will now describe the manner of carrying my invention into effect, reference being had to the appended sheet of drawings, in which Figure 1 is a vertical cross 30 section of the press, Fig. 2 a side elevation thereof, and Fig. 3 is an enlarged vertical sectional view taken through the table and the follower, showing the celluloid sheet entering the recess in the follower.

In these drawings A is the table or bed of the press and B the head, platen or follower, which is operated mechanically from the 40 crank shaft C so that the head B can be brought toward the table A by turning the hand wheel D the latter operating the crank shaft through the gear wheels E and F.

The table A is provided with a recess with 45 inclosing sides to receive the matrix G, and the head or follower B of the press is either recessed to receive the inflatable sack or mattress or the equivalent arrangement may be provided namely providing the follower with a recess to the margin of which an india 50 rubber diaphragm is attached so as to form a mattress H. The table or bed A of the press has a hollow chamber I in it into which steam can be injected through the pipe J for heating the matrix G or into 55 which cold air or other fluid can be driven through the pipe K for cooling. This chamber I is also provided with a steam safety valve L which will automatically open to permit steam to escape should the pressure 60 exceed a given limit. A release or exhaust valve M for steam is also provided. An air pressure pipe N from the air pump passes into the head B of the press to the mattress H through which pipe the air is 65 driven into the mattress H. The mattress

is provided also with an air pressure release valve O, and the press is provided with air pressure, steam pressure, and safety valve air pressure gages P Q and R.

In operation the matrix G is laid in the 70 recess in the table A, the sheet of celluloid S or other analogous material is applied, and the steam through the pipe J is now turned on so as to heat the matrix G and the celluloid sheet laid thereon. The inflatable mattress face of the follower is brought toward the table so that the mattress H will lie against the sheet S which enters slightly into the recess in the follower so that the sides of the recess lie closely all around the 75 celluloid sheet thus holding the celluloid sheet in position, and yet allow of any air or any gas or liquid between the celluloid sheet S and the matrix to escape laterally at the edges of the sheet because there is no 80 tight clamping of the inflatable mattress face of the press against the table, there being in fact a clear open space T between the two faces. The pump is now put into operation and pumps air through pipe N into 85 the mattress H and compresses it therein and pressure is maintained in the mattress for just so long as it is necessary to cause the surface of the celluloid sheet to be molded on the matrix. The air pump is now 90 stopped and the steam shut off, and cooling fluid is injected into the table or base A of the press through the pipe K so as to cool the matrix and harden the sheet. The head B and table A of the press are separated and 95 the molded sheet of celluloid is taken out and (when mounted on a block to make it type high) is used as a surface for printing from.

In the operation described the rubber face 10 of the mattress presses the celluloid sheet on to the matrix by which a replica of the matrix is produced in relief or intaglio on the celluloid sheet. The celluloid is forced into all the interstices or depressions in the matrix and is molded in such manner as to produce a plate without striations or bubbles for printing letter-press, pictures, posters, paper hangings and so on.

My improved printing plates can of course 11 be made flat in which case a flat matrix is used to mold them, or they can be made of curvilinear shape as required for rotary printing or for wall paper and calico printing rollers in which case a curved matrix is required.

I declare that what I claim is:—

An apparatus of the character described comprising a table, a matrix carried by the table, a follower having a recess, an inflatable mattress in said recess above the lower edge thereof, said follower and mattress being spaced from the table in lowered position whereby when the follower is brought down to its lowermost position, the sheet 11

laid upon the matrix will partially enter the recess below the mattress while permitting the gas or liquid between the sheet and the matrix to escape through the space between the table and the follower.

In witness whereof, I have hereunto signed my name this 21st day of December

1917, in the presence of two subscribing witnesses.

ALFRED JAMES NEILL WALKER.
